CUT-OFF LENGTH INDICATING
MECHANISM

Hobart W. Bruker, Bordentown, N. J., assignor
to George W. Swift, Jr. Inc., Bordentown,
N. J., a corporation of New Jersey

Application May 15, 1939, Serial No. 273,645

7 Claims. (Cl. 164—68)

The invention relates to cut-off mechanisms such as are used to cut up lengths of corrugated paper board or the like into blanks of predetermined lengths, and in its more specific aspects the invention has special reference to machinery of the above character in which the knife mechanism is continuously driven and the material to be cut is fed continuously past the knife mechanism, means such as a variable speed transmission being provided to adjust the frequency of operation of the knife mechanism and thereby regulate the length of the cut blanks. It frequently is desired to have such machines operate at high speeds and with precise accuracy of cut, as well as with quick and accurate adjustment while running, and heretofore the practice has been to provide the variable speed transmission with an indicating dial which was automatically shifted in position during adjustment of the variable speed transmission and which was supposed to indicate the length of cut corresponding to the various settings of the variable speed transmission. However it has resulted from a variety of causes that length indicators of the above character have not been accurate and reliable in actual practice, so that the operator could not be sure that blanks would be produced corresponding to the indicated length, nor could he be sure that a given correction, or deviation from the indicated length of cut, would give him accurately the length of blank he wanted. Frequently blanks had to be removed as delivered by the machine, measured for length, corrections in setting made, and then more blanks removed and measured, etc., in an effort to check the accuracy of cut from time to time and conform the length of cut to specification.

The primary object of the present invention accordingly is to provide a mechanism for indicating the length of cut which may be relied upon to show quickly and accurately for any desired setting, how the length of blank which the machine is actually producing, compares with specifications and the corrections in setting if any which are necessary to conform to specifications. Further related objects and advantages of the invention will be in part obvious and in part specifically referred to in the description herein-after contained which, taken in conjunction with the accompanying drawings, discloses a cut-off machine having an indicating mechanism applied thereto which is constructed to operate in accordance with the invention. It should be understood, however, that many changes may

be made without departing from the invention in its broader aspects.

In the drawings—

Fig. 1 is a central longitudinal sectional view taken through a cut-off machine constructed to operate in accordance with the invention.

Fig. 2 is a transverse section taken on the line 2—2 of Fig. 1 and looking in the direction of the arrows.

Fig. 3 is a detail top plan view of part of the 10 machine shown in Fig. 1.

Fig. 4 shows detached a panel board carrying push buttons which may be used in making certain of the adjustments.

The invention is disclosed as applied to a continuously driven cut-off of the type shown in United States patent to G. W. Swift, Jr., No. 2,059,412, dated November 3, 1936, and since the specific construction and mode of operation of many of the parts of such a machine are not essential to the present invention, they will not be described in detail herein. For present purposes the machine may be understood as having a servo-motor 47 (as numbered in the above Swift patent) which adjusts the setting of a variable speed transmission (as marked 42 in the Swift patent) for the purpose of regulating the length of cut, and also a servo-motor 32 which by altering the position of suitable variable motion mechanism not necessary to be described herein, alters the cutting speed of the knife mechanism so as to keep the speed of cut substantially equal to the speed of travel of the web 38 to be cut. The particular machine illustrated has cooperating cutters or knives 1 and 2 of the rotary type, carried respectively by rotary shafts 1a and 2a, which are interconnected by spur gears 4 and 6. The sheet 38 may be fed past the knives 1 and 2 by suitable feed rollers 37 associated with the cut-off machine or adjacent machinery.

In accordance with the present invention I provide along the path of travel of the web 38 as it passes through the machine, a length of cut indicating mechanism which is driven in timed relation to the knives 1 and 2, this mechanism being adjustably mounted for movement toward and away from the knives, so that it may be spaced from the knives a distance equal to the length of the blank desired to be cut. Then, assuming that this indicating mechanism imposes a mark on the web 38 at the same time that the cutters 1 and 2 come into conjunction to cut the blank, the mark will indicate precisely where one end of the cut blank should be, at the 55

same time that the cutter 2 is defining the other end edge of the blank. If the above mentioned indicating mechanism is located ahead of the cutters, it will mark where the position of the rear edge of a particular blank should be, at the same time that the cutters are defining the front edge thereof, and then if there is any error in the setting of the machine for length of cut, this will be visually indicated to the operator as the web 38 continues to travel through the machine, since the cutters will cut either ahead of or behind the mark when the marked portion of the sheet passes between them. Or if the marking mechanism is located behind the cutters so that it operates upon the forward portion of a blank at the same time that the cutters are defining the rear edge thereof, the mark will be placed just at the previously formed forward edge of the blank if the machine is properly cutting to length, and if the machine is not properly set the operator may readily observe that the mark is not being placed in its proper location, and will then operate the servo-motor 47 to make the adjustment in the setting of the variable speed transmission which is necessary to correct the error. Thus, so long as the operator sets the length indicating mechanism at the proper distance from the cutting position of the knives, which distance may be readily indicated upon a scale, the length indicating mechanism gives him an immediate and reliable indication as to whether the mechanism is cutting to the desired length, and if not indicates to him the corrections necessary to be made.

In the illustrated form of the invention the length indicating mechanism above referred to, consists of a rotary arm 50 carried by a shaft 51, which extends crosswise of the machine on the delivery side of the cutters 1 and 2, the ends of the shaft 51 being journaled in brackets 52 which are slideable lengthwise of the machine along longitudinally extending ways 53. The sheet marking member 50 is driven in timed relation to the cutter 2a by means of a splined longitudinally extending spindle 54 journaled in fixed bearings 55 and 56 at its opposite ends, and carrying a bevel gear 57 which meshes with a bevel gear 58 on shaft 2a. One of the brackets 52 carries an arm 59 in which a bevel gear 60 is rotatably mounted, this gear 60 surrounding the spindle 54 and being splined thereto. A bevel gear 61 is fixed to the adjacent end of shaft 51 and meshes with bevel gear 60, the construction being such that whenever brackets 52 are moved toward or from the cutter mechanism, the arm 59 and associated parts move along with the brackets, the splined connection between gear 60 and spindle 54 permitting the movement and the spindle 54 at all times driving marking member 50 in timed relation to the cutter 2.

The arm 50 may carry at its outer end a small printing die 62 which receives ink from a suitable inking roller 63, so as to mark a line, dot or other suitable mark upon the web 38, each time the arm 50 comes around to the web-engaging position shown in Fig. 1. The arm 50 is so coordinated in angular position with the knife 2 that it impresses a mark on web 38 at the same time that the knife 2 begins to cut through the web, and the distance between the active portion of the die 62 and the cutter 2 will then correspond to the length of blank desired to be cut, i. e., the operator will have adjusted the position of the brackets 52 so that this distance equals the length of blank which he wishes to cut. Then

if the machine is properly set for length of cut, the mark made by the die 62 will be impressed just at the forward edge of the blank which is then having its rear edge cut out by the cutter 2. If the mark should be impressed, for example, one-eighth of an inch behind the forward edge of the blank, the operator will know that his machine is cutting one-eighth of an inch too long, and will operate the servo-motor 47 until the mark comes just at the forward edge of the blank. The position of the brackets 52 may be readily adjusted by suitable means such as a cross shaft 64 journaled in the two brackets and carrying gears 65 which mesh with racks 66 on the tops of ways 53, shaft 64 being operated by a suitable hand crank 67. The distance between the die 62 and the cutter 2 when the last mentioned parts are in active position (which distance corresponds to the length to which the blanks are desired to be cut) may be indicated in any suitable manner as by a pointer 68 on one of the brackets 52 which overlies a scale 69 on a table 70. Suitable conveyor belts 71, running around rollers 72 and 73 will usually be employed as previously known in the art, to feed the cut blanks along to the point of delivery.

It should be noted that the length indicating mechanism is not dependent for its accuracy upon any constancy of relationship between the various parts of the variable speed transmission for a given length of cut, and likewise in respect to the parts of the mechanism used to conform the cutting speed of the cutters to the speed of travel of the material being cut, or other parts of the cutter driving train proper.

The mechanism which indicates or measures the length of cut as compared to the desired length of cut, being positively related to the knives by connecting driving mechanism which is in turn connected to the knife driving train at a point located on the delivery side, so to speak, of the variable speed transmission, is not affected as to accuracy by any irregularities in operation of the variable speed transmission. For similar reasons the length of cut indicator will not be thrown out of phase with the knives, by adjustments of the means (whatever such means may be) for conforming the cutting speed of the knives to the speed of travel of the material being cut, since this last mentioned means also comes ahead of the indicator in the driving train. In other words, even though the variable speed transmission or other parts of the driving train should wear or alter the relationship of one part to another for any other cause, either temporarily or permanently, such changes will not be reflected in or affect in any way the length indicating mechanism, since the latter depends only upon a proper setting of the carriage which is made up of the brackets 52 and associated parts, such that the length indicating member 50 operates at the selected distance from the knife 2 when the latter is beginning to cut. The driving parts between the cutter 2 and the indicating member 50 may be readily made so that they are not appreciably affected by wear or other causes of inaccuracy such as have existed in connection with length of cut indicating mechanism used heretofore for similar purposes. Thus once the scale 69 be initially set correctly, accurate length indications are normally obtainable over the entire life of the machine.

In operating the machine, the operator will stand in a position convenient to observe the operation of the indicating mechanism, and he will

have located at his operating station, a suitable control board 74 as indicated in Fig. 4, carrying for example a "forward" push button 75 and a "reverse" push button 76 controlling the servo-motor 47 for either increasing or decreasing the length of cut as may be desired; and also a "forward" push button 77 and a "reverse" push button 78 for controlling the servo-motor 32, to increase or decrease the cutting speed of the cutters in order to conform this cutting speed to the speed of travel of the web 38, as known in the art. After the machine has been accurately set to produce blanks of one given length it is frequently feasible to throw the indicating member 50 out of operation by disconnecting clutch 79 in spindle 54, so that the indicating mechanism is not used during the remainder of the run. And while the run of blanks is being completed, the carriage consisting of the brackets 52 and associated parts may be moved to the proper setting for the length of blank to be cut during the next run. Upon completion of the first run and throwing in clutch 79, which clutch should be of single jaw or equivalent construction (such that the marking member 50 always runs in proper phase with knife 2) the indicating marks will of course be out of coincidence with the edges of the blanks, and the operator will operate push button 75 or 76 as the case may be, until the indication marks coincide with the edges of the blanks to be cut during the run, and also he will operate push button 77 or 78 as the case may be, to conform the cutting speed of the cutters to the speed of travel of web 38. This latter operation will also conform the speed of travel of the die 62 when in its active position, to the speed of travel of web 38. Depending upon the ratios of the gears 51, 53 and 60, 61, the indicating member 50 may be arranged to afford an indication for each blank as the latter is cut, or less frequently.

A mechanism of the above character has important advantages from the standpoint of eliminating waste or blanks cut to odd lengths, since on account of the inaccuracies of the dials heretofore used it has been customary to set dial initially to a length somewhat longer than desired, and then shorten the setting gradually until measurements on successive blanks show that a blank of the desired length is being cut. By the use of a mechanism operating in accordance with the present invention, an accurate setting can be much more quickly and reliably arrived at, thus reducing the number of odd length blanks produced in the meantime.

The invention also has substantial advantages from the standpoint of labor saving. According to prior practice, cut blanks are delivered upon a "take-away" table requiring a "take-away" man to jog and place them on their proper trucks. And in addition to this "take-away" man, it has been necessary to have another man to set the dial for the length of sheet required, inspect and measure the blank for proper length. In fact when the machine was running short orders, e. g., 200-300 blanks of one size, it took the entire time of one man to look after the setting of the dial. Using a mechanism operating in accordance with the present invention, the scale 69, as well as the push buttons 75-78, may be readily so positioned that the "take-away" man can check the blanks as to length and make any necessary adjustments in the length of cut, along with his other duties.

While the invention has been disclosed as car-

ried out by machinery of certain specific construction, it should be understood that many changes may be made therein without departing from the invention in its broader aspects within the scope of the appended claims.

I claim:

1. In combination, a cut-off knife of the continuously driven type, a variable speed transmission in the driving train of said knife, means for adjusting said variable speed transmission to alter the frequency of operation of said knife, a marking mechanism located in the path of travel of material being fed past said knife and in spaced relation to said knife, means for driving said mechanism in timed relation to the knife to periodically mark such material, means whereby the amount of said spacing may be adjusted, and a length of cut indicator associated with said marking mechanism.

2. In combination, a rotary cut-off knife of the continuously driven type, a variable speed transmission in the driving train of said knife, means for adjusting said variable speed transmission to alter the frequency of operation of said knife, a carriage mounted to be movable toward and from said knife along the path of travel of material being fed past the knife, a periodically operating rotary marking mechanism mounted upon said carriage, means for driving said mechanism in timed relation to the knife, and means for indicating the spacing between said mechanism and the knife.

3. In combination, a cut-off knife of the continuously driven type which is constructed and arranged to operate periodically on the material being cut, means for altering the frequency of operation of said knife, and a length of cut indicator positioned to operate on the material being fed past the knife, said indicator being positively driven in timed relation to the cutter, and means whereby the spacing between said indicator and said cutter may be altered.

4. In combination, a cut-off knife of the continuously driven type, a variable speed transmission in the driving train of said knife, a length of cut indicator located in the path of travel of material being fed past said knife and in spaced relation to said knife, said length of cut indicator being positively connected to a moving part in the knife driving train which is located on the delivery side of said variable speed transmission, said length of cut indicator being also driven in timed relation to the knife and being adjustably mounted to be movable toward and from said knife.

5. In combination, a cut-off knife of the continuously driven type, a driving train for said knife including in series a variable speed transmission adjustable to regulate the frequency of cut of said knife, an adjustable means for conforming the cutting speed of the knife to the speed of travel of the material being cut, a length of cut indicator located in the path of travel of material being fed past said knife and in spaced relation to said knife, said indicator being mounted to be movable toward and from said knife, said indicator being positively connected to a moving part in the knife driving train which is located on the delivery side of said variable speed transmission and cutting speed conforming means, and being also driven in timed relation to the knife.

6. In combination, rotary cut-off knives of the continuously driven type and having a driving train including means for altering the frequency

of operation of said knives, a carriage mounted to be movable toward and from said knives along the path of material being fed past the knives, a periodically operating rotary marking mechanism mounted upon said carriage, means for positively driving said mechanism in timed relation to the knives including a shaft positively driven from moving parts in said driving train which are adjacent said knives, said shaft being slidably coupled to said marking mechanism, and means for indicating the spacing between said mechanism and the knives.

7. In combination, a cut-off knife, means for periodically operating said knife to cut material fed to the knife, said means being adjustable to vary the frequency of operation of said knife, a length of cut indicator located in the path of material being fed past said knife and in spaced relation to said knife, means for periodically operating said indicator in timed relation to the knife, said indicator being adjustably mounted to be movable toward and from said knife. 5 10

HOBART W. BRUKER.
